(57) **CLAIM**

The ornamental design for a jumpsuit as shown and described.

DESCRIPTION

FIG. 1 is a front perspective view of a jumpsuit showing our new design;

FIG. 2 is a front view thereof;

FIG. 3 is a rear view thereof;

FIG. 4 is a left side view thereof;

FIG. 5 is a right side view thereof; and,

FIG. 6 is a rear perspective view thereof.

The broken lines in the drawings depict portions of the jumpsuit that form no part of the claimed design.

1 Claim, 6 Drawing Sheets
